Howson & Howson

UNITED STATES PATENT OFFICE.

TRON O. PETERSON, OF NEW YORK, N. Y., ASSIGNOR TO ROXFORD KNITTING COMPANY,
OF PHILADELPHIA, PENNSYLVANIA, A CORPORATION OF PENNSYLVANIA.

GARMENT.

1,202,578.

Specification of Letters Patent.

Patented Oct. 24, 1916.

Application filed July 30, 1915. Serial No. 42,819.

To all whom it may concern:

Be it known that I, TRON O. PETERSON, a citizen of the United States, and a resident of New York, N. Y., have invented certain 5 Improvements in Garments, of which the following is a specification.

My invention relates to combination garments or, as they are usually termed, "union suits," and it is more particularly directed 10 to garments of this character which are employed as "undergarments."

My invention consists of an improved seat construction for such garments, which seat construction is available or adaptable for 15 close or loose-fitting garments, for men, women and children, whether made of elastic or non-elastic material, or of a combination of elastic and non-elastic materials; such improved seat construction increasing 20 the comfort, protection and convenience of the wearer and improving the appearance and wearing qualities of the garment.

My invention resides in slitting the garment across the back adjacent to the lower 25 part of the body portion of the same; such slit lying substantially within a plane passing substantially through the joints of the hip bones of the wearer and terminating at each side of the garment substantially opposite 30 the points of the hip bones, and in providing a cover for such slit portion which cover is permanently attached to the garment downwardly from the ends of the slit.

An improved garment is thus provided in 35 which the necessary opening may be produced by drawing the edges of the slit apart and pulling down the lower cover portion or seat of the garment when the wearer assumes a sitting posture; advantage being 40 taken of the fact that the part of the body to be exposed by the opening provided by the slit forms substantially a segment of a sphere of which a line passing substantially through the hip joints is the axis.

The edges of the slit are preferably permitted to overlap to a greater or less extent, and the upper portion of the back of the garment may extend downward as a short skirt, which skirt may be disposed inside 50 or outside the upper edge of the lower cover portion. Buttons and buttonholes, or any other form of fastening means may be provided for keeping the slit closed. These and other features of my invention are more

fully described hereinafter, reference being 55 had to the accompanying drawings, in which:

Figure 1, is a side elevation of a garment made in accordance with my invention; Fig. 2, is a rear elevation of the same; Fig. 3, shows the position of the garment when the 60 wearer makes use of the seat opening in a sitting posture, and Fig. 4, is a view illustrating a slight modification within the scope of my invention.

My improved garment may be made of 65 any of the various knitted or woven fabrics, or a combination of the same employed with various forms of garments and undergarments now in use, and the feature of my improved garment is the character of the 70 seat opening and the cover or closure therefor.

The garment 1 shown in the accompanying drawings is an ordinary one-piece combination, or union suit, which may have the 75 usual opening vertically down the front of the same, or any other arrangement to permit the wearer to enter the suit, and a transverse opening or slit indicated substantially at 2, extending across the back, which slit 80 may be held closed by means of buttons 3, or any other suitable form of fastening devices. In Fig. 1, this slit is shown as extending across the back of the garment in a nearly horizontal plane, but it may be disposed either higher or lower radially from 85 the point a, as at a—b or a—c.

The back of the garment is preferably brought down over the top of the buttocks with a slight skirt 5, while the lower portion 90 of the back of the garment carries the cover or seat portion 6, the top edge of which may extend in a substantially horizontal line around the back of the body between points opposite the joints of the hip bones, or radially along the lines a—b or a—c, while its sides are permanently attached to the garment downwardly from the ends of the transverse opening or slit. The skirt 5 may 95 be disposed inside or outside the cover portion 6, and such skirt is preferably reinforced with a band 7 which may carry the buttons or other fastening devices 3. The terminals of the slit preferably extend forward of the actual center of the body so that 100 the length of the portion included within the slit or opening 2 is usually more than half of the entire peripheral dimension of 105

the garment in a plane which cuts through the joints of the hip bones.

The curvature of the buttocks in normal individuals follows substantially the arc of a circle struck from a line passing through the joints of the hip bones as an axis, and by having the top of the cover 6 in a line extending substantially radially from the joint of the hip bones, it is possible to lower 10 the cover for necessary purposes by sloping or pushing the same down around the lower part of the buttocks when assuming the sitting posture. Fig. 3 shows a side view of the garment with the opening or slit spread 15 apart by swinging the edge of the cover member 6 radially in such a manner as to expose part of the body of the wearer, such figure also showing the extension or skirt 5 of the upper portion of the garment depending downward below the line of the edge of the slit.

When the garment is made of knitted material, it may fit the body close, in substantially the manner illustrated in Figs. 1, 2 25 and 3, but if made of woven material, which is relatively inelastic, it is desirable to supply the seat with a greater amount of fullness, as illustrated in Fig. 4. The extra fullness may be produced by cutting the material 30 which is to form the seat or cover portion 6 below the edge of the slit longer than would be necessary to enable it to close an opening on the line 2, or as though it were to close an opening on the line $a-b$, and by allowing it 35 to drop to position along the line 2, greater fullness is given to the garment between the line 2 and the points $a-d$; sufficient for the desired purpose. In both instances, however, the cover 6 may be readily slipped 40 around the buttocks when assuming the sitting posture as indicated in Fig. 3, without danger of any portion of the garment hanging down or falling into the bowl and becoming liable to fouling.

45 The skirt 5, which may underlie or overlie the cover or seat portion 6, is sufficient to prevent all danger of the garment gaping at the back, and this skirt may extend around the back the full depth. The front portion 50 of the garment may be open to the crotch or otherwise constructed, and may be secured by buttons as indicated at 3^a, or by any other suitable form of securing means. The seat portion or cover 6 may be provided, preferably at its upper edge, with any suitable form of adjusting means; such as an elastic

gore section 8; straps 9, with buckles or buttons as may be desired, or draw-strings 10.

It will be understood, of course, that the point a represents substantially the axis of 60 the hip joint and that in the main my improved construction bears a definite relation to such point. In the development of certain sizes of my improved garment, however, it may be necessary to place the point a forward or back of the hip joint, but in all instances it will lie substantially in the plane of the hip joints.

I claim:

1. A combination union garment provided with a posterior opening, said opening formed by a transverse slit extending across the back of the garment, the lower posterior portion of the garment below the slit constituting a cover or seat portion and permanently connected to the sides of the garment from the ends of said slit downwardly. 70

2. A combination union garment provided with a posterior opening, said opening formed by a transverse slit extending across 80 the back of the garment, the lower posterior portion of the garment below the slit constituting a cover or seat portion and permanently connected to the sides of the garment from the ends of said slit downwardly, and 85 fastening means for detachably securing the edges of the slitted portion of the garment together.

3. A combination union garment provided with a posterior opening, said opening 90 formed by a transverse slit extending across the back of the garment substantially below the waist line, the lower posterior portion of the garment below the slit constituting a cover or seat portion and permanently connected to the sides of the garment from the ends of said slit downwardly, and fastening means for detachably securing the edges of the slitted portion of the garment together. 95

4. A combination union garment provided with a posterior opening, said opening formed by a transverse slit extending across the back of the garment, the lower posterior portion of the garment below the slit constituting a cover or seat portion and permanently connected to the sides of the garment from the ends of said slit downwardly, fastening means for detachably securing the edges of the slitted portion of the garment together, and means for laterally adjusting 100 the upper edge of said cover or seat portion. 105

TRON O. PETERSON.
